UNITED STATES PATENT OFFICE.

HENRY H. OUVERSON, OF HANLONTOWN, IOWA.

PUMP STAND OR HEAD.

Application filed April 8, 1922. Serial No. 550,718.

To all whom it may concern:

Be it known that I, HENRY H. OUVERSON, a citizen of the United States, residing at Hanlontown, in the county of Worth and 5 State of Iowa, have invented certain new and useful Improvements in Pump Stands or Heads, of which the following is a specification, reference being had to the accompanying drawings.

10 This invention relates to pumps, and particularly to the pump stand or head of a pump.

The general object of my invention is to provide a permanent standard which can 15 be fastened permanently to the well cover or casing and which will detachably support the usual dome, the spout section and the pump jack or other operating mechanism, and which is so constructed that when the 20 pump needs to be repaired, the pumping head may be readily removed to permit the drop pipes, cylinder, etc., of the pump to be pulled out of the well without removing this base or standard.

25 A further object is to provide a pump construction of the character described including a standard large enough in diameter to permit the passage therethrough of the drop pipes, cylinder, etc., and to provide a 30 spout section detachably engaged with the standard to which the drop pipe is secured, and provide a dome section detachably secured to the spout section and provide means whereby the pump jack may be detachably 35 secured to the dome section, thus making all of these parts in separate sections so that in case of breakage they may be readily replaced or renewed without having to renew the entire pump, and furthermore 40 making the pump mechanism capable of repair without the necessity of taking up the pump standard or disturbing the pump jacks or other machinery.

A still further object is to provide means 45 whereby the relatively long drop pipes may be readily removed from the pump.

Another object is to so construct the base or 50 standard that not only may the objects above described be secured but the standard will make a very strong support for the pump jacks or other machinery and will render the pump structure much more substantial than it otherwise would be.

55 Still another object is to so construct the pump head that the first coupling of the plunger rod, which very often gives trouble,

can be readily repaired without the necessity of and expense of pulling the pump out of the well and of removing the drop pipe, as has to be done in the ordinary form of 60 pump.

Other objects will appear in the course of the following description.

My invention is illustrated in the accompanying drawings, wherein:

65 Figure 1 is a front elevation of a pump constructed in accordance with my invention;

Figure 2 is a vertical sectional view taken from front to rear of the pump;

70 Figure 3 is a section on the line 3—3 of Fig. 2;

Figure 4 is a side elevation of the dome and pump jack removed from the body of 75 the pump;

Figure 5 is a side elevation showing the base or standard of the pump with the draw pipe 19 and the section 14 removed therefrom;

Figure 6 is an enlarged fragmentary sectional view to show the details of the section 80 14;

Referring to these drawings, 10 designates a pump standard, which is illustrated as circular in cross section, though any cross 85 section may be used, and as being relatively large in diameter. The upper end of this standard 10 is formed with an annular flange 11, the upper face of which is below the upper end of the central portion or hub 90 12. The lower end of the pump standard is outwardly and downwardly flared to form a base portion 13 which is attached by bolts, screws or other well known devices to the well cover or equivalent part.

95 Adapted to be disposed upon the upper end of the standard is a flat section or head 14 which is preferably, though not necessarily, circular in cross section, and is formed on its under face with a seat 15 to 100 receive the upwardly extending hub 12 and with a downwardly extending, annular flange 16 resting upon the flange 11, there being a gasket 17 disposed between the flange 11 and the flange 16. There is a central chamber 18 formed in the interior of the section 14 and a central inlet opening which is interiorly screw-threaded for engagement with the drop pipe 19. The upper face of the section 14 has a central outlet 105 opening 20 and a depressed seat 21 surrounding this opening. Extending laterally 110

from the chamber 18 is an outlet duct 22 which discharges into a detachable spout 23. This spout, as illustrated in Figure 2, is shown as flanged at its base, as at 24, and is attached by screws 25 to the section 14. Any other obvious means of detachably securing the spout to the section 14 may be used, however.

Disposed above and resting upon the section 14 is the dome section 26, which is of the usual form, the lower end of this dome section being formed with a central hub fitting into the seat 21 and an annular flange 27 which rests upon the section 14. Bolts 29 pass downward through a bolt passage formed in the section 14 and through bolt openings formed in the flanges 27 and 11, these bolts therefore holding the section 14 to the standard 10 and the dome 26 to the section 14. The upper end of the section 26 is formed with a relatively contracted neck 30, the lower portion of which has the outwardly projecting flange 31. Surrounding this neck and resting upon the flange 31 is a head 32 having a packing gland 33 at its upper end through which the pump rod 34 passes, this head being held to the dome section by means of bolts 35, the lower ends of which are angularly turned to engage beneath the flange 21. This section 32 supports the usual pump jack, which need not be specifically described, as it is of ordinary form and in common use.

As before remarked, the drop pipe 19 has screw-threaded engagement with the head 14. Passing through this drop pipe is the pump rod section 36, the lower end of which carries a piston 37 operating within a cylinder 38, in turn connected to the pipe 39. This pump rod section 36 is connected by the usual coupling 40 to the upper pump rod section 34.

It will be obvious that this pump, which may be operated by power, as for instance by a windmill, motor, or in any other suitable manner, operates and is used in the ordinary manner, but if a part of the pump head or pumping mechanism breaks, however, then it will be seen that it is a relatively easy matter to remove the broken part or section and replace it with a new section. Thus this broken part may be replaced at a small cost instead of having to buy an entirely new pump head. Inasmuch as the spout 23 is removable from the section 14, it is obvious that any spout now on the market may be utilized, and it is an easy matter to procure a new spout in case the old spout becomes broken. Ordinarily, if the spout or pump becomes broken, it is necessary to entirely replace the pump head. With this construction, when the pump needs to be repaired the drop pipe, plunger rods and cylinder may be pulled up out of the well and up through the lower half of the pump stand 65 after detaching section 26. That part of the

stand fastened to the platform of the pump need not be molested. Neither does the pump jack need to be detached other than to uncouple the levers where they engage the plunger rod of the pump. This operation is accomplished by removing the bolts 29 which hold the three sections of the pump head together. Then the drop pipes and cylinder may be readily removed for the reason that the base 10 or standard has a diameter greater than the diameter of the cylinder or any of the parts of the pump which extend through or depend below the cylinder. The drop pipe, it will be noted, is secured to the section 14, and by this arrangement the difficulty is avoided of making a water-tight joint at the junction of the section 14 with the standard. The joint between the sections 14 and 26 need only have sufficient packing to take care of the splashing of the water or the rising of the water into the dome above when the pump is operated.

In taking up the drop pipe from the well, section 14 need not be uncoupled from the pipe, thus eliminating danger of breaking the casting while unscrewing it from the pipe. In the ordinary pump, the stand or head is often broken in disconnecting it from the drop pipe. Coupling 40 is the first or top coupling in the plunger rod of any pump. In the ordinary pump this coupling cannot be reached without detaching the entire pump head from the drop pipe, as the ordinary head is cast in one piece and the drop pipe is screwed into the stand. In my pump stand, however, the coupling 40 may be reached by simply taking off the upper half of the stand or section 26.

The first coupling, or coupling 40, of the plunger rods very often gives trouble and this may be readily repaired by simply taking off section 26 of the dome section without removing or shifting any of the other parts, thus saving the trouble and expense of pulling the pump out of the well and removing the drop pipe, as has to be done in the ordinary type of pump.

Not only does the standard 10 by reason of its large diameter permit the removal of the drop pipe and cylinder without removing the standard, but this large standard materially increases the life of the pump, as it makes a very strong support for the pump jacks or other machinery and renders the pump, therefore, much more substantial than ordinary pumps where the pump is run by windmills or other power.

It is particularly emphasized that the primary advantage of my pump stand is due to the fact that the cylinder, pipes and plunger rods may be taken up out of the well without disturbing the principal part of the stand or head which is fastened to the

stand or platform of the well. This is impossible to do with pumps as ordinarily constructed.

While I have illustrated certain details of construction and arrangement of parts which I believe to be particularly effective, I do not wish to be limited to these details, as it is obvious that many changes might be made therein without departing from the spirit of 10 the invention as defined in the appended claims.

I claim:

1. In a pump, a hollow standard flanged at its upper end, a spout section resting upon 15 the flange of the standard and having a central chamber, a dome section resting upon the spout section and communicating with the inner chamber thereof, a spout attached to the spout section and communicating with 20 the inner chamber thereof, bolts passing through the flanges of the dome section, the spout section and the upper end of the standard and engaging these three parts together, and a drop pipe detachably engaged 25 with the spout section and discharging into the central chamber thereof, the standard having an interior diameter greater than the drop pipe or any part connected thereto.
2. In a pump, a hollow standard, a drop 30 pipe extending downward through the standard and carrying a pump cylinder at its lower end, a spout section detachably engaged with the upper end of the standard and connected to the upper end of the drop 35 pipe, a dome section detachably engaged with and resting upon the spout section and

provided at its upper end with a pump head, a plurality of bolts passing vertically through the spout section and detachably connected to the adjacent ends of the standard and the dome section, thereby connecting said parts together axially, the standard having a diameter greater than the drop pipe and greater than the pump cylinder, whereby the drop pipe and the cylinder may 45 be passed upwardly or downwardly through the standard.

3. In a pump, a hollow standard, a spout section detachably engaged with the upper end of the standard and having means to 50 align the sections axially with the standard, a dome section detachably engaged with and resting upon the spout section and including means for aligning the dome section with the spout section axially, a plurality of connectors passing through the spout section and detachably connected with the adjacent ends of the standard and the dome section for drawing together and axially connecting 55 said parts, a drop pipe depending from the 60 spout section and extending downward through the standard and carrying a pump cylinder at its lower end, the standard being of a diameter greater than the pump cylinder, whereby the cylinder may pass upwardly through the standard, when the drop pipe is hoisted upwardly through the standard. 65

In testimony whereof I hereunto affix my signature.

HENRY H. OUVERSON.
